UNITED STATES PATENT OFFICE.

PAUL E. HEINZE, OF CHICAGO, ILLINOIS, ASSIGNOR TO JOHN F. WOLLEN-
SAK, OF SAME PLACE.

DESIGN FOR A SPEAKING-TUBE WHISTLE.

SPECIFICATION forming part of Design No. 12,322, dated June 21, 1881.

Application filed March 31, 1881. Term of patent 7 years.

To all whom it may concern:

Be it known that I, PAUL ERNST HEINZE, of the city of Chicago, in the county of Cook and State of Illinois, have originated and invented a new and useful Design for Speaking-Tube Whistles; and I do hereby declare the following to be a full, clear, and exact description thereof, reference being had to the accompanying drawing, forming a part of this specification.

In the drawing, A represents the cylindrical shell; B, the flaring mouth-piece; C, the extended speaking-tube; a, the spherical end of the shell, and b the flat end.

I claim and desire to secure—

The design for a speaking-tube whistle, having the cylindrical shell or barrel A, of a plain exterior surface, and with the mouth-piece and the flat end b and the spherical end a, in combination with the flaring mouth-piece B and the extended tube C.

In witness whereof I have hereunto set my hand this 26th day of March, A. D. 1881.

PAUL ERNST HEINZE.
